His Attorney.

UNITED STATES PATENT OFFICE.

JACOB O. JOYCE, OF DAYTON, OHIO.

LIFTING-JACK.

SPECIFICATION forming part of Letters Patent No. 276,827, dated May 1, 1883.
Application filed February 26, 1883. (No model.)

To all whom it may concern:

Be it known that I, JACOB O. JOYCE, a citizen of the United States, and a resident of Dayton, in the county of Montgomery and State of Ohio, have invented certain new and useful Improvements in Lifting-Jacks, of which the following is a specification.

My invention relates to a lifting-jack.

The object of my invention is to furnish a cheap, portable, and rapidly-working device adapted to raising light weights—such as railway-tracks and other work which requires frequent shifting of the jack—all of which will be fully set forth in the description of the accompanying drawings.

Figure 1 represents a vertical central section of my improvement. Fig. 2 is an elevation of the top portion of the device shown transversely to Fig. 1. Fig. 3 is a section on line *y*, Fig. 2. Fig. 4 is a section on line *xx*, Fig. 2.

A represents the base of the frame; *B*, the barrel or stock of the jack, through the bore of which loosely slides the screw-threaded lifting-bar *C*.

c represents the lifting-foot.

D *D* represent segmental lugs, preferably cast on and with the stock or barrel *B*. These lugs are grooved upon their inner sides, and form a bearing for the nut-collar *E*, which is provided with an annular flange, *E'*, journaling in the grooved segmental lugs *D*.

H *H'* represent lever-sockets cast on and with the collar *E*.

The base of the frame *A* is slotted through, so as to allow the lifting-bar *C* *c* to be inserted into the stock or removed therefrom.

a represents the open slot or mortise in the base *A*.

The segment form of lugs *D* *D* allows the collar-nut *E* to be inserted in position or removed therefrom when the lifting-bar *C* has

been run down so as to disengage the threads of the bar *C* from those of collar-nut *E*. Thus the jack is readily put together and taken apart, as well as being light and portable.

Instead of having the lever-sockets *H* *H'* rigidly attached to the collar-nut *E*, the barrel of the collar might be made many-sided and be operated by a wrench; or the exterior of the collar might be made to engage with a ratchet-lever in common use in lifting-jacks; but such modifications would still be embraced in the first clause of claims herein.

I claim—

1. A lifting-jack combining in its structure the barrel *B*, supported by a base, and having upon its upper end stationary lugs, an interiorly-screw-threaded collar, *E*, swiveled between the said lugs, which serve to prevent vertical movement thereof, and a screw-threaded lifting-bar, *C*, substantially as described.

2. The combination, in a lifting-jack, of the barrel *B*, provided with a base, *A*, and lugs *D*, fixed on its upper end, and having their inner ends grooved, with the interiorly-threaded collar *E*, having an annular flange, *E'*, located in the grooves of the lugs, and a screw-threaded lifting-bar, *C*, substantially as described.

3. The combination, in a lifting-jack, of the barrel *B*, supported by a base, and having lugs *D* *D* fixed on its upper end, with an interiorly-threaded collar, *E*, swiveled to the lugs, and constructed with laterally-projecting lever-sockets *H* *H'*, substantially as described.

In testimony whereof I have hereunto set my hand in the presence of two subscribing witnesses.

JACOB O. JOYCE.

Witnesses:

M. E. MILLIKAN,
JNO. E. JONES.
